MARCO GUIDO, OF NORTH PLYMOUTH, MASSACHUSETTS.

SHOE PRESS.

Application filed March 7, 1928. Serial No. 259,786.

This invention relates to shoe presses, and has more particular reference to an improved apparatus for use in cementing soles and heels upon the uppers of footwear in the manufacture or repair thereof.

More specifically, the present invention aims to provide an improved form of press embodying means to support a shoe upper, and means to firmly clamp a heel, a half-sole, or a whole sole in place upon the upper while the cement for securing the parts to the upper, sets and hardens.

A further object is to provide a shoe press of the above kind which may be conveniently used for effective operation upon shoes of various sizes.

Still another object is to provide a shoe press of the above kind adapted to be conveniently mounted upon a conventional shoe maker's bench, and having simple and practical provision for permitting the major portion of the apparatus to be removed from the bench when not required for use.

A further object is to provide a shoe press so constructed as to permit the sole or heel applying operation to be carried out conveniently and expeditiously.

Still another object is to provide means for effectively steadyng footwear provided with high heels, when operating upon the latter.

Yet another object is to provide a shoe press of the above kind, which is extremely simple and durable in construction, efficient in use, and adapted to be economically manufactured as well as readily placed into use without the requirement of especial skill.

The invention consists in the novel form, combination and arrangement of parts hereinafter more fully described, shown in the accompanying drawings and claimed.

In the drawings:

Figure 1 is a side elevational view of a shoe press embodying the present invention;

Figure 2 is a top plan view thereof;

Figure 3 is a horizontal longitudinal section on line 3—3 of Figure 1;

Figure 4 is a transverse vertical section taken on line 4—4 of Figure 1;

Figure 5 is a plan view of a supplemental last adapted for use upon the permanent last of the shoe jack in Figure 1, when operating upon footwear of larger than a given size;

Figure 6 is an edge elevational view of the device shown in Figure 5;

Figure 7 is a top plan view of a presser plate employed when applying whole soles;

Figure 8 is an edge elevational view of the device shown in Figure 7;

Figure 9 is a fragmentary view, partly in vertical section and partly in side elevation, illustrating the manner of using the devices of Figures 5 to 8 inclusive in connection with the press of Figures 1 and 2;

Figure 10 is a top plan view of a presser plate adapted to be employed when applying half-soles;

Figure 11 is a central transverse section on line 11—11 of the device shown in Figure 10;

Figure 12 is an edge elevational view thereof;

Figure 13 is a top plan view of a supplemental last block adapted for use in the heels of high heel shoes when the latter are operated upon with the press of Figures 1 and 2; and

Figure 14 is a side elevational view of the device shown in Figure 13.

Referring more in detail to the drawings, the present shoe press embodies an elongated base plate 5 provided with side flanges 6 apertured as at 7 for the reception of screws or other fastening elements whereby the base plate may be firmly secured upon the top of a shoemaker's bench or the like. This base plate is provided with a longitudinal undercut groove 8 in the upper surface thereof, which groove is preferably of dove-tail form in transverse section as shown clearly in Figure 4 and is also of gradually tapered form in plan or horizontal section so that the walls gradually converge from one end to the other as shown in Figure 3. The groove 8 is adapted for snug reception of a correspondingly-shaped and tapered longitudinal rib 9 provided upon the base 10 of a shoe jack, which shoe jack embodies a pedestal 11 rigid with and rising from the base 10 at the wider end of the rib 9 and having an integral last plate 12 on its upper end.

The pedestal 11 is thickened or reinforced at its lower end as at 13 so as to form a supporting post rising from the base 10 and having a pair of spaced superposed openings,

one of which is indicated by dotted lines at 14, and the other of which is shown as having a removable pivot pin 15 engaged therein for pivotally connecting an inverted U-shaped 5 yoke 16 to the post 13. A similar post 17 is rigid with the forward end portion of the base 10 and rises therefrom beneath the toe portion of the last 12. This post 17 is also provided with a pair of spaced superposed 10 openings, one of which is shown by dotted lines at 18, and the other of which is shown as having a removable pivot pin 19 engaged therein for pivotally connecting a second inverted U-shaped yoke 20 through the post 17. 15 As clearly illustrated in Figures 1 and 2, the yokes 16 and 20 are of sufficient length and width as to pass the sides of the last 12 and to extend across and in spaced relation to and above the last 12 when the yokes are vertically 20 positioned. The pivot pins 15 and 19 are selectively engageable in desired ones of the openings 14 and 18 for permitting vertical adjustment of the yokes 16 and 20, whereby the device may be used for operation upon 25 shoes having soles or heels applied of various thicknesses. It will of course be understood that the lower ends of the legs of the yokes 16 and 20 are formed with transversely aligned openings to receive the respective pivot pins 30 15 and 19 when the latter are engaged in desired ones of the openings 14 and 18 to pivotally attach the yokes 16 and 20 to the posts 13 and 17. As the openings 18 extend transversely of the base 10, the yokes are pivotally 35 mounted for swinging movement longitudinally of the last 12 for movement into and out of position at the sides and above the latter. Obviously, this permits convenient application of the upper of an article of footwear to 40 the last 12 as well as removal of the upper with its applied sole or sole and heel from the last 12.

All of the parts thus far described are carried by the base 10 of the last, except the base 45 plate 5 from which said base 10 is readily detachable for convenient removal when in the way or not required for use.

The intermediate horizontal portion of the yoke 16 has a clamping screw 21 adjustably 50 threaded therethrough for firm clamping engagement with the heel of a shoe or with the heel portion of a presser plate when the parts are disposed as shown in Figures 1 and 9, a foot 22 being preferably swiveled upon the 55 inner or lower end of the screw 21 for engagement with the shoe heel or presser plate whereby free turning of the screw 21 is facilitated. A similar clamping screw 23 is likewise adjustably threaded through the intermediate portion of the yoke 20 for engagement 60 with the presser plate at or adjacent the ball of the sole portion of said presser plate. It is thus apparent that when the device is set as in Figures 1 and 9, the downward adjustment of the screws 21 and 23 may be ef-

fected for firmly clamping the sole, heel or half-sole in place upon the upper, whereby effective union of the parts is insured if the screws are not released until after the cement is allowed to set and harden. 70

Rigid with and projecting rearwardly and downwardly from the intermediate portion of the yoke 16 is an arm 24 having a forwardly and downwardly inclined clamping screw 25 adjustably threaded through the free end 75 thereof, said clamping screw 25 being thus composed to have its swiveled foot 26 impinge the back of the shoe heel so as to steady the shoe when operating upon shoe uppers provided with high heels. 80

It is to be understood that in using the present press, the shoe upper is placed in an inverted position upon the last 12, whereupon the part to be united to the bottom of the shoe upper is placed upon the latter, a suitable cement or adhesive being employed to effect union of the shoe part in a generally well known manner. When applying whole soles, a presser plate of the form shown in Figures 7 and 8 is placed upon the whole sole 90 27 as shown in Figure 9, whereupon the yokes 16 and 20 are swung upwardly to a vertical position so that the clamping screws 21 and 23 overlie the heel and sole portions of the presser plate as shown in Figure 9. The 95 screws 21 and 23 are then adjusted downwardly into engagement with the presser plate for firmly pressing the sole against and holding it in place upon the bottom of the shoe upper, whereby a proper and effective 100 union of parts is insured when the screws are left in clamping adjustment until the cement or adhesive sets and hardens. When the sole applying operation has been completed, the screws may be manually backed 105 away from the presser plate, after which the yokes 16 and 20 may be swung downwardly 110 away from each other or in opposite directions so as to be out of the way and permit ready removal of the presser plate and the finished article of footwear. As shown, the presser plate 28 for use in applying whole soles is adapted to be made for use in connection with right and left shoes and in various sizes to properly clamp different sizes 115 of whole soles. Each whole sole presser plate will embody a sole portion 29 and an upwardly offset heel portion 30, the sole portion 29 being provided with a central longitudinal thickened portion 31 on its upper side 120 provided with a longitudinal series of spaced shallow pockets or depressions 32 for selective reception of the lower end of the clamping screw 23, in accordance with the adjustment of the presser plate with regard to certain different sized soles. In this way, firm engagement of the screw 23 with the presser plate is insured so that the latter is effectively held in place against accidental lateral and 125 longitudinal movement after the desired 130

130

pressure has been applied. Moreover, the rounded lower end of the screw 23 acting in the circular depressions 32 provides a relatively small end thrust pivot insuring ease 5 of turning of the screw 23 when the pressure is applied.

When applying half-soles, a presser plate of the form shown in Figures 10 to 12 inclusive is preferably used. As shown, this 10 half sole presser plate consists of a metallic plate member 33 substantially conforming in shape to the form of the half sole and having a central longitudinal series of pockets or 15 depressions 34 serving the same function as the depressions or pockets 32 of the presser plate 28. A rubber or other resilient spacing 35 is provided on the under surface of the plate 33 and provided with a raised marginal rib 36 for engagement with the margin of the 20 half-sole, thereby insuring that greatest pressure will be applied at the margin of the half-sole where union of the latter with the sole portion of the upper is most essential. It will of course be understood that when 25 applying half-soles and using the presser plate of Figures 10 to 12 inclusive, said presser plate will be firmly held and pressed against the half sole by the use of the clamping screw 23, the heel of the shoe being impinged by the foot 22 of the screw 21 so that the shoe is effectively steadied and held in place while the cement sets and hardens, the 30 screw 25 being adjusted into engagement with the back of the shoe heel to additionally steady the same when such shoe heel is of the high heel type. In case the shoe upper is somewhat larger than the last 12, a supplemental or auxiliary last is placed thereon for reception 35 of the shoe upper as shown in Figures 5, 6 and 9, the supplemental last being sufficiently larger than the last 12 to properly fit within and fairly snugly receive this larger size of shoe upper. As shown, this supplemental last consists of a metal plate having 40 a sole portion 37 curved to fit upon the sole portion of the last 12 and having a heel portion 38 provided with crossed central longitudinal and transverse ribs 39 and 40 upon its underside adapted to hold the heel portion 38 at the desired elevation above the heel portion of the last 12 as is necessary with the larger sizes of shoe uppers. The ribs 39 and 40 will contact the heel portion of the last 12 at the lower edges as shown in Figure 9, 45 and the transverse rib 40 effectively prevents lateral tilting of the auxiliary or supplemental last. These auxiliary or supplemental lasts are made for right and left shoes and of various sizes larger than the last 12 of the shoe jack.

When operating upon high heeled shoes or the like, a special heel-last block is preferably employed upon the heel portion of the last 12 or the supplemental last 37, 38. This heel 50 last block is shown at 41 in Figures 13 and 14

and preferably consists of a hollow cast metal shell of proper shape and height and open at the bottom as will be clearly indicated by the dotted lines in these figures. At the back of the heel last block 41 is a depending transverse rib 42 adapted to engage the rear edge of the last 12 or the last plate 37, 38, to insure retention of the block 41 in proper position and against forward displacement when in the heel portion of the shoe upper. 70

The operation has been dealt with in detail as the specific description has progressed, and it is accordingly believed that the specific construction and manner of use of the invention will be readily appreciated and understood by those skilled in the art, without further detail comment thereon. It will be apparent that the invention provides simple and efficient means for expeditiously performing the operations enumerated above. 80 Minor changes may be made without departing from the spirit and scope of the invention as claimed. 85

What I claim as new is:—

1. In a shoe press of the character described, a shoe jack, yokes having clamping screws and hinged to the base of the jack to swing to and from operative position with the screws respectively overlying the heel and sole portions of the jack last, and means 90 permitting vertical adjustment of the screw-carrying portions of the yokes.

2. In a shoe press of the character described, a shoe jack, yokes having clamping screws and hinged to the base of the jack to swing to and from operative position with the screws respectively overlying the heel and sole portions of the jack last, and means to hinge the yokes in vertically adjusted positions relative to the jack. 100

3. In a shoe press of the character described, a shoe jack, yokes having clamping screws and hinged to the base of the jack to swing to and from operative position with the screws respectively overlying the heel and sole portions of the jack last, a rearwardly and downwardly projecting arm on the yoke at the heel portion of the jack, and a clamping screw carried by said arm adjustable into engagement with the heel of a shoe disposed on the jack last to steady the shoe. 110

4. In a shoe press of the character described, a shoe jack, yokes having clamping screws and hinged to the base of the jack to swing to and from operative position with the screws respectively overlying the heel and sole portions of the jack last, and a presser plate embodying a sole engaging member, said sole engaging member having a longitudinal series of depressions in its upper surface for selective seating reception of the clamping screw of the yoke at the sole portion of the jack. 120

5. In a shoe press of the character described, a shoe jack, yokes having clamping 130

screws and hinged to the base of the jack to swing to and from operative position with the screws respectively overlying the heel and sole portions of the jack last, a presser plate embodying a sole engaging member, said sole engaging member having a longitudinal series of depressions in its upper surface for

selective seating reception of the clamping screw of the yoke at the sole portion of the jack, and a yielding facing on the lower surface of said presser plate having a continuous depending marginal rib. ¹⁰

In testimony whereof I affix my signature.

MARCO GUIDO.
